[57] CLAIM

The ornamental design for a seal for a container cap or outlet port, as shown and described.

DESCRIPTION

FIG. 1 is an end elevational view of a seal for a container cap or outlet port showing our new design;

FIG. 2 is a top plan view;

FIG. 3 is a side elevational view, the opposite side being a mirror image thereof;

FIG. 4 is a sectional view taken on the line 4—4 of FIG. 2;

FIG. 5 is an elevational view showing the end opposite that shown in FIG. 1; and

FIG. 6 is a bottom plan view.
